UNITED STATES PATENT OFFICE.

JOHN O. ROLLINS, OF SAWTELLE, CALIFORNIA.

BOTTLE CLOSURE.

Application filed December 5, 1921. Serial No. 519,982.

To all whom it may concern:

Be it known that I, JOHN O. ROLLINS, a citizen of the United States, residing at Sawtelle, in the county of Los Angeles and State of California, have invented certain new and useful Improvements in Bottle Closures, of which the following is a specification.

This invention relates to bottle closures, and it comprises a stopper or disk of card-board or similar material adapted to be received in a groove formed in the neck of a bottle, said stopper being provided with openings, closure members arranged in said openings and resilient means for securing said stopper positively in position in the neck of the bottle.

In the present invention I provide a stopper for milk bottles and the like having a pair of openings arranged near opposite sides of the stopper, these openings being normally closed by plugs or closure members which are readily removable for the purpose of pouring the contents of the bottle. In pouring, one of the openings serves as an outlet for the fluid in the bottle and the other as an inlet for air to replace the discharged liquid. This permits the contents of the bottle to be removed without removing the stopper.

I further provide means for preventing the stopper from dropping out of the neck of the bottle when the bottle is tilted to pour the liquid from one of the openings, said means consisting of a resilient ring, preferably formed of metal, adapted to engage within the groove at the top of the bottle. The ends of the ring are provided with finger grips.

In the drawings, I have shown one embodiment of the invention. In this showing—

Figure 1 is a side elevation of the bottle, parts being shown in section, showing the invention applied,

Figure 2 is a plan view,

Figure 3 is a perspective view of the neck of a bottle showing the closure members removed,

Figure 4 is a sectional view on line 4—4 of Figure 2,

Figure 5 is a plan view of the retaining ring, and

Figure 6 is a detail perspective of one of the closure members.

Referring to the drawings, the numeral 1 designates a bottle provided with an opening 2 at its upper end. The opening is provided with an under-cut groove 3 for the reception of a stopper. The usual stopper employed consists of a disk of card-board, which is usually slightly larger than the upper portion of the groove 3 and is adapted to be inserted therein.

In the present invention I provide a stopper 4 consisting of the usual disk provided with openings 5 arranged near opposite sides of the stopper. The openings 5 are normally closed by closure members 6 having flanges 7 which engage the upper face of the support. The closure members 6 are held in position by frictional engagement with the edges of the openings 5. It will be obvious that the closure members 6 may be readily removed by inserting a sharp instrument beneath the flanges 7.

The foregoing description of the bottle to which this invention relates applies to the type of milk bottle now in common use, as will be obvious. In the manufacture of these bottles it has been found that the diameter of the opening in the bottle varies slightly with different makes of bottles. It will be obvious, therefore, that if the stopper 4 were employed with a bottle having an opening of slightly larger diameter than is usual, there would be danger of the stopper becoming unseated from the groove 3.

In order to positively maintain the stopper in position while milk or other liquid is being poured from the bottle, I employ a retaining member 8 preferably in the form of a ring, as shown. The retaining ring is preferably formed of resilient metal and is provided upon opposite sides with swaged portions 9 which are preferably triangular in cross-section as clearly shown in Figure 4, with their lower faces lying flat against the upper face of the stopper 4. The ring 8 is preferably provided upon its ends with upwardly extending portions 10 terminating in off-set portions 11 which are arranged par-

lel to and spaced from each other. The portions 11 of the ring serve as convenient finger pieces in applying the ring to the bottle and removing it therefrom. As shown, the 5 ring 8 is normally inserted within the groove 3, against the upper face of the stopper and since the diameter of the ring across the 10 portions 9 thereon is slightly greater than the diameter of the lower portion of the groove 3, these portions 9 will grip the sides of the groove and positively maintain the ring in position.

It will be obvious that when the closure members 6 are removed the bottle may readily be tilted to pour the contents therefrom without danger of the stopper 4 becoming unseated. When it is desired to remove the stopper from the bottle, the ring 8 may be removed by pressing inwardly upon the 20 finger pieces 11, whereupon a hook or similar instrument can be inserted within one of the openings 5 and the stopper removed.

It is to be understood that the form of my invention herewith shown and described is 25 to be taken as a preferred example of the

same, and that various changes in the shape, size, and arrangement of parts may be resorted to without departing from the spirit of the invention or the scope of the subjoined claim.

Having thus described my invention, I claim:

The combination with a bottle provided with a groove in its open end forming a shoulder and a disk mounted within the 35 groove and resting upon the shoulder, of a resilient split wire ring provided upon its ends with finger grips, said ring being mounted against said disk and being provided with outwardly swaged portions upon 40 opposite sides providing sharpened edges to grip against the walls of the opening of the bottle above the shoulder therein.

In testimony whereof I affix my signature in presence of two witnesses.

JOHN O. ROLLINS.
